MASS SPECTROMETER

Clifford E. Berry, Pasadena, Calif., assignor to
 Consolidated Engineering Corporation, Pasadena, Calif., a corporation of California

Application June 17, 1948, Serial No. 33,596

9 Claims. (Cl. 250—41.9)

1

This invention relates to mass spectrometers in general and in particular to an improved and simplified ion source for a mass spectrometer. The invention also relates to fabrication methods employed in the construction of the improved ion source.

A mass spectrometer is an analytical apparatus which functions to sort and measure ions. Ordinarily it includes an ionization chamber into which molecules of the sample to be analyzed are introduced. In the ionization chamber the molecules are bombarded by a stream of electrons and converted into ions. So-called propelling or accelerating electrodes propel the ions from the ionization chamber into and through an analyzer chamber. The ionization chamber, sample inlet, electron source and accelerating electrodes are, in accordance with the instant invention, formed into a single mechanical unit referred to as the "ion source."

During passage through the analyzer chamber the ions are subjected to a transverse electric or magnetic field or both, to separate them according to their mass-to-charge ratios into a plurality of diverging beams of ions. Each ion beam is composed of ions of the same specific mass and differing from the ions in the other beams. The diverging beams are successively focused on an ion collector by varying the potential applied to the accelerating electrodes or by varying the intensity of the transverse field in the analyzer tube. The current produced by the discharge of each beam on the ion collector is a measure of the partial pressure of the molecules (from which the ions were derived) in the sample being analyzed.

In accordance with the present invention, there is provided an ion source which possesses a number of advantages both with respect to application and function over the conventional ion source. Some of these advantages are listed to facilitate an understanding of the objectives of the invention.

1. The number of separate parts required has been materially reduced.
2. The function of insulating and mounting the several parts is accomplished by one member instead of a plurality of members.
3. The parts are attached in definite and stable position by brazing them to their supporting members.
4. Closely adjacent surfaces which can hold contaminating material and thus slow down evacuation have been eliminated.

The foregoing and other improvements are

2

accomplished in accordance with the invention by the construction of an ion source comprising an insulating plate having a plurality of conductive wires or rods sealed therethrough. A series of metal parts are mounted over all or a part of the plurality of rods and are held there-to and in appropriate relationship to each other by brazing to one or more of the rods. The series of metal members form successively from the insulating disk a sample inlet, an ionization chamber, pusher electrodes housed in the ionization chamber, a first ion slit, a second ion slit, and a third ion slit. An electron emitting filament is mounted adjacent an outer wall of the ionization chamber. The filament emits an electron beam which is directed through a slit in the wall and transversely across the ionization chamber.

A feature of my invention is the combined function of the plurality of conducting rods which serve (1) as supports to which the several parts are affixed and (2) as electrical leads supplying appropriate potentials to the various parts of the ion source. Additionally, the rods permit spacing of the various parts to (1) facilitate cleaning, (2) eliminate closely adjacent difficultly evacuated surfaces, and (3) insulate the necessary parts from each other.

The invention will be more clearly understood with reference to the following detailed description taken in relation to the accompanying drawings wherein:

Fig. 1 is a partial sectional view of a mass spectrometer showing the relationship of the ion source of the invention to the sample inlet means and analyzer tube;

Fig. 2 is a section view of the ion source;

Fig. 3 is a horizontal section taken on the line 3—3 of Fig. 2;

Fig. 4 is a vertical section taken on the line 4—4 of Fig. 3;

Fig. 5 is an exploded view of the ion source showing each of the elements thereof in perspective; and

Fig. 6 is a bottom perspective view of the laterally aligned element of Fig. 5.

Referring to the drawing and particularly to Fig. 1 thereof, the ion source 10 is shown mounted within the inlet end of a mass spectrometer 11. The mass spectrometer includes an analyzer tube 12 and an evacuating tube 14. Generally, the evacuating tube 14 is connected to apparatus capable of producing a high degree of vacuum such as a molecular pump, mercury diffusion pump or the like. The evacuating tube 14 opens through

a wall of a tubular member 13 which surrounds the ion source 10 and from which the analyzer tube 12 projects.

A tubular member 17, projecting into tubular member 13, is clamped between flange 24, attached to tube 13, and a flange 16, and serves to support the ion source inside tube 13. The ion source includes a plurality of conducting rods 1, 2, 3, 4, 5 (see Fig. 5), shown in Fig. 1 projecting downwardly from the ion source. In the mounting as shown, a circular metal disk 22 is brazed to the several rods 5, and is in turn bolted to the top of the tube 17.

The tube 13 is provided at its lower end with a flange 24 which rests against a flange 25 formed on the lower end of the tube 17. The tube 17 in turn rests against the flange 16. The flange 25 on tube 17 is provided with electric inlet leads 26, 27 through which the several rods 1, 2, 3 and 4 of the ion source 10 may be connected to a voltage supply circuit to establish appropriate potentials at the various parts of the ion source. The rods 5 which are connected through the metal plate 22 in conductive relationship to the tube 17 are at the same potential as the tube 17.

The ion source 10 includes a nipple 28 extending through the disk 22 and the top of the tubular member 17. The nipple 28 is connected to a sample source (not shown) by means of a flexible sample inlet tube 30 extending through the tubular member 17 and the flange 16.

The construction of the ion source 10 can best be understood by reference to Figs. 2, 3, 4, 5 and 6. Referring first to the exploded perspective view of Fig. 5, the ion source includes an insulating plate 34, a first disk 35 through which the inlet nipple 28 is affixed, split pusher electrodes 36, 37, a second disk 38 having a recess 40 which forms an ionization chamber with the adjoining face of the disk 35 and having a first ion slit 42 in the top thereof, a third disk 44 defining a second ion slit and a fourth disk 45 defining a third ion slit.

The plate 34 is conveniently fabricated of glass and preferably glass having a coefficient of expansion approximating that of the conductive rods sealed therethrough. Preferably the rods are tungsten. The construction of an insulating disk of this type with such rods sealed therethrough is described in detail in my co-pending application Serial No. 760,196, filed July 11, 1947, and entitled Metallic-Glass Joints.

As shown in Fig. 5 the plate 34 contains 15 straight tungsten wires or rods of varying lengths arranged in two concentric circles; 6 in the inner circle and 9 in the outer. Some of the wires project through the back surface of the disk a short distance so that appropriate electrical connections can be made to them. Two spaces in the outer concentric circle are unfilled, leaving a blank section of glass which is ground off to form a flat face 34A. A hole 48 is drilled in the middle of the plate through which the gas inlet tube 28 projects (see Fig. 4). The various tungsten rods are denoted by numerals from 1 to 5. These designations will be used to identify the rods when the mounting of the various parts is described.

The disk 35 is made from a solid piece of metal, generally circular in plan with the exception of a flat face 35A. When the ion source is assembled, the face 35A coincides with the surface 34A of the insulating plate 34. The disk 35 is provided with a central hole 58 into which the inlet nipple 28 is brazed. There are 15 holes drilled in the block to match the 15 rods projecting from the plate 34.

Each of these holes is made larger than the rods so that no connection exists when the disk 35 is placed on the plate 34. The clearance between the rods and so called "clearance holes" in the successive disks is clearly apparent in Figs. 2 and 4.

The several clearance holes in the disks and pusher electrodes are designated by numerals corresponding to the numbers of the support rods which extend through these holes. Thus the number 2 rods project through the clearance holes 2A in the disk 35.

Ferrules 60, 61, 62, and 63 (Figs. 3 and 4) are brazed into the holes 3A in the disk 35. When this disk is mounted on the plate 34 as shown in Figs. 2, 3 and 4, the rods 3 project through the ferrules 60, 61, 62, and 63 and are brazed thereto to hold the disk and the plate together in spaced relationship.

In attaching the metal disk 35 to the glass plate 34, a spacing of a few thousandths of an inch is maintained between the block and the disk by means of removable spacers. After completing the assembly, the spacers are removed leaving sufficient space so that the adjoining faces of the block and the disk may be readily cleaned. In the drawing the several members are shown touching each other; it being impossible to illustrate a spacing in the order of magnitude of a few thousandths of an inch. Additionally, although highly desirable, such spacing is not absolutely essential to the functioning of the ion source.

As mentioned above, one of the objects of the invention is to provide an ion source wherein closely adjacent surfaces are eliminated so as to reduce the consequent interference with evacuation. The term closely adjacent surfaces, as applied relative to an ion source operating at reduced pressures, refers to metal surfaces which are actually touching. In such case, because of microscopic unevenness in the adjoining faces, evacuation is impeded. The spacing of a few thousandths of an inch provided between the disk 35 and the plate 34 is considered in this application to be a large space in that it is of such magnitude as not to interfere with the evacuating process.

The disk 35 is provided with two oppositely located peripheral notches 64 and 65 which form thin lips 64A, 65A, in the top of the disk. These lips are used as hereinafter described, for spot welding the disk 38 to the disk 35.

In my co-pending patent application Serial No. 763,886, filed July 26, 1947, and entitled Welding, and relating to the fabrication of ionization chambers for mass spectrometers, it was pointed out that difficulties are encountered in brazing the various parts of an ionization chamber or ion source to tungsten leads such as the rods extending from the plate 34. Since the brazing alloy melts at about 1600° C. it is impossible to heat the whole assembly including the glass plate 34 to this brazing point without damage. Further, a difficulty normally encountered in the brazing operation is splattering of the molten alloy; even microscopic splatters of the material on the glass plate or on other parts of the ion source will cause subsequent difficulties in operation.

In the last mentioned co-pending application I described the construction and use of ferrules such as the ferrules 60, 61, 62 and 63 whereby the foregoing difficulties were eliminated. As there described, the ferrule has a cup-shaped upper

portion forming an annulus around the rod in which a brazing, welding, or soldering material is disposed. With the cup held relatively upright, heat is applied to the outside of the ferrule from below. By conduction through the ferrule the annulus to be fused attains the necessary high temperature. In that application I described a resistance element for supplying the necessary heat to the annulus to be brazed. This positioning of the cup, soldering element, and heating element, completely avoids spattering of the solder or other welding material after it becomes fused and provides an intense localized heat for the fusing operation without necessitating application of intense heat to the whole apparatus.

The recess 40 in disk 38 forms, with the adjoining face of disk 35, an ionization chamber in which ionization of the sample molecules takes place. Disposed in the chamber and directly above the disk 35 are pusher electrodes 36 and 37. These electrodes comprise two D-shaped members conveniently constructed by splitting a disk into two parts. Each electrode is provided with a hole 2B (Fig. 5) alignable with the rods 2 projecting from the glass plate 34. Ferrules 66, and 67 are brazed in the holes 2B and the rods 2 projecting from the glass plate are brazed to the ferrules to hold the electrodes in spaced and fixed relationship to the other parts.

Proceeding with the description of the apparatus in the order of assembly, a small rectangular gold member 70 is brazed to the upper end of wire 1 which projects through a clearance hole 1A in the disk 35. The gold rectangle 70 forms an electron catcher as more fully described hereinafter.

The second disk 38 contains 8 clearance holes through which all of the rods numbered 4 and 5 project without touching the disk. These several clearance holes are designated either 4B or 5B, to indicate which of the rods 4 and 5 project therethrough and are in alignment with the holes 4A and 5A in the disk 35.

As hereinbefore described, a recess 40 is formed in one face of the second disk leaving a thin face 72 on the other side of the disk. A slit 42 is cut in the face 72 and serves as a first ion slit.

A flat 38A is formed across one side of the disk in alignment with the flat faces 35A and 34A of the members 35 and 34 respectively for the like purpose of providing space for an electron emitting filament 74 (Fig. 2). A thin lip 75 is left above the flat surface 38A to act as a shield for the filament 74. A slit 76 is cut in the flat 38A opening into the chamber formed by the recess 40. A somewhat larger slit 78 is cut in the opposite side of the recess 40 giving access to a smaller recess 79 in which the electron catcher 70 is placed. Electrons generated by the filament pass as a beam through the slits 76 and 78 and impinge on the electron collector 70. During traversal of the chamber 40, the electrons ionize the sample molecules therein.

The disk 38 is provided with oppositely spaced peripheral notches 80 and 81 in alignment with the notches 64 and 65 in the disk 35. The notches 80 and 81 form thin lips 80A and 81A in the lower edge of the disk 38. The first and second disks are joined by spot welding the lips provided by the several notches (see Fig. 4). A space of a few thousandths of an inch is provided between the parts during assembly to allow cleaning of the surfaces and to eliminate closely adjacent surfaces for the reasons given above.

The member 44 comprises a split disk forming two D-shaped parts 44A and 44B. These form a second ion slit 44C. Each of parts 44A and 44B is provided with holes 4C and 5C through which the rods 4 and 5 project. Ferrules 82, 83, 84 and 85 are brazed into each of the holes 4C in the members 44A and 44B, and the appropriate rods are brazed thereto.

The member 45 comprises a disk having a recess 86 in one face thereof leaving a thin opposite face 87. The face 87 is provided with a slit 88 therein. The disk 45 is provided with holes 5D in which ferrules 90, 91, 92, and 93 are brazed. (Figs. 2 and 4.)

15 As illustrated in the drawing, all of the clearance holes as well as all of the holes in the ferrules are oversize in order to reduce the precision necessary in the location of the wires and the ferrules. In assembling the ion source, all of the parts are held in correct position by an accurate fixture and are brazed together while so held. Thus, in the final assembly the wires are not strained in any way and there is no distortion in the ion source when removed from the fixture.

20 25 As shown in Figs. 2 and 4 the plate 34 is provided on both its upper and lower surfaces with strengthening bosses around each of the wires with the exception hereinafter noted. There are no supporting bosses in the upper face of the

30 plate around wires 1 and 2 (Fig. 2). For purposes of clarity in Fig. 5 all of the bosses are eliminated from the plate 34. The reason for eliminating the upper bosses around wires 1 and 2 is to reduce gas leakage from the ionization chamber through the holes 1A, 2A and 1B in the disks 35 and 38. Thus, as above described, these clearance holes are made larger than the wires for the double purpose of avoiding contact of the wires with the blocks 35 and 38 and also for the

40 purpose of facilitating assembly of the ion source. Gas leakage through these holes will be directly proportional to their size and inversely proportional to their length. It follows that by elimination of the upper bosses from the disk 44 the length of the holes 1A and 2A will be increased and gas leakage will be reduced. This is not a necessary feature of the invention but is illustrated as a preferred embodiment thereof.

45 Although one specific means of mounting the ion source of the invention in a mass spectrometer is illustrated in detail in Fig. 1, it is to be understood that the ion source is designed for use in substantially any mass spectrometer. The means of mounting the ion source within any given instrument will be determined by the design of the mass spectrometer. The present invention is not intended to be limited to the mounting of the ion source as shown in Fig. 1.

50 The feature of the invention which involves the mounting of the several parts of the ion source to different ones of a plurality of semi-rigid rods projecting from an insulator plate 34 is not limited to the particular configuration of rods shown in the drawings. Thus, for convenience in manufacturing, the plurality of supports are arranged in two concentric circles as shown in Fig. 5. However, any arrangement may be employed and the relative positioning of the shorter and longer rods may be interchanged

55 60 65 70 without interfering with the functioning of the ion source. Any rearrangement will, of course, necessitate relocation of the clearance holes in the several members. In short, the illustrated 75 arrangement of the rods with respect to each

other is not essential to the proper functioning or construction of the ion source.

Not only have I provided an ion source which is greatly simplified with respect to the number of parts and compactness over conventional ion sources, but the ion source of the invention further possesses the advantage of simple construction and assembly. One of the aspects of the invention is the method of fabrication which comprehends the relative positioning of the several parts of the ion source in a fixture so that each is in engagement with one or more of the several wires projecting from the plate 34. While held in the fixture the several parts are brazed to the appropriate wires. By such a practice the ion source is constructed as a unit and may be inserted or withdrawn from the mass spectrometer as a unit. The advantages of this type of construction and method of fabrication with respect to manufacture and with respect to periodic cleaning of the ion source, are manifest.

I claim:

1. In an ion source for a mass spectrometer the combination which comprises a first conductive disk having an inlet therein for molecules to be ionized, a second conductive disk affixed against the first disk and having recess therein opening toward the first disk and defining an ionization chamber, the second disk having an ion slit in it opposite the first disk, a third conductive disk having an ion slit in alignment with the ion slit in the second disk and spaced from the second disk on the side opposite the first disk, a plurality of conductive supports passing through the several disks, and means affixing the first disk and the third disk to separate ones of the said supports.

2. In an ion source for a mass spectrometer the combination which comprises a first conductive disk having an inlet therein for molecules to be ionized, a second conductive disk disposed against the first disk and affixed thereto and having a recess therein opening toward the first disk and defining an ionization chamber, the second disk having an ion slit in it opposite the first disk, a pair of pusher electrodes suspended in the ionization chamber independent of the first and second disks, a third conductive disk having an ion slit in alignment with the ion slit in the second disk and spaced from the second disk on the side opposite the first disk, a fourth conductive disk having an ion slit in alignment with the ion slit in the third disk and spaced from the third disk on the side opposite the second disk, and plurality of conductive supports passing through the several disks and means affixing the first, third and fourth disks and the pusher electrodes to separate ones of said supports.

3. In an ion source for a mass spectrometer the combination which comprises a first conductive disk having an inlet therein for the molecules to be ionized, a second conductive disk disposed against and affixed to the first disk and having a recess therein opening toward the first disk and defining an ionization chamber, the second conductive disk having an ion slit in it opposite the first disk, a pair of pusher electrodes suspended in the ionization chamber independent of the first and second disks, a third conductive disk having an ion slit in alignment with the ion slit in the second disk and spaced from the second disk on the side opposite the first disk, a fourth conductive disk having an ion slit in alignment with the ion slit in the third disk and spaced from the third disk on the side opposite the second disk, and plurality of conductive supports passing through the several disks and means affixing the first, third and fourth disks and the pusher electrodes to separate ones of said supports.

7
8
third disk on the side opposite the second disk, a plurality of conductive supports passing through the several disks, means affixing the first, third, and fourth disks and the pair of pusher electrodes to separate ones of said supports, and means for anchoring the plurality of supports in fixed relationship to each other.

4. Apparatus according to claim 3 wherein the means for anchoring the several supports comprises a glass plate through which the conductive supports are sealed.

5. In an ion source for a mass spectrometer the combination which comprises a first conductive disk having an inlet therein for molecules to be ionized, a second conductive disk disposed against and affixed to the first disk, a first recess in the second disk opening toward the first disk and defining an ionization chamber, a second recess in the second disk opening toward the first disk, a first slit in the second disk communicating between the first recess and the second recess, a second slit in the second disk communicating between the first recess and the exterior of the disk opposite the first slit, a third slit communicating with the first recess opposite the first disk, a third conductive disk having an ion slit in alignment with the third slit in the second disk and spaced from the second disk on the side opposite the first disk, a plurality of conductive supports passing through the several disks, means affixing the first and third disks to separate ones of said supports, one of said supports extending into the second recess in the second disk, an electron catcher mounted on said one of said supports, and an electron emitting element disposed adjacent said second disk in alignment with said second slit therein.

6. In an ion source for a mass spectrometer, the combination which comprises a plurality of conductive rods sealed through a sintered glass plate, and means mounted to separate ones of the plurality of rods to form an ionization chamber, pusher electrodes and accelerating electrodes the means forming the pusher electrodes and accelerating electrodes being spaced from each other and from the means forming the ionization chamber.

7. In an ion source for a mass spectrometer which comprises an ionization chamber having sample inlet means, pusher electrodes disposed in the ionization chamber and accelerating electrodes, the improvement which comprises a sintered glass disk, a plurality of conductive rods sealed through the disk, the ionization chamber, pusher electrodes and accelerating electrodes being mounted to separate ones of said plurality of rods in spaced relationship to each other.

8. In an ion source for a mass spectrometer having several component parts including means for ionizing molecules and means for discharging ions from the ion source, the improvement which comprises a plurality of conductive members sealed through an insulating member and spaced from each other, the several component parts of the ion source being mounted to different ones of said conductive members in spaced relationship.

9. In an ion source for a mass spectrometer, the combination which comprises a plurality of conductive rods sealed through an insulating member, and means mounted to separate ones of the plurality of rods to form an ionization necessitate relocation of the clearance holes in the several members. In short, the illustrated arrangement of the rods with respect to each

each other and from the means forming the ionization chamber.
